OIL BAILER

Filed March 16, 1922 2 Sheets-Sheet 2

UNITED STATES PATENT OFFICE.

FRED M. KIDDER, OF WARREN, PENNSYLVANIA.

OIL BAILER.

Application filed March 16, 1922. Serial No. 544,221.

To all whom it may concern:

Be it known that I, FRED M. KIDDER, a citizen of the United States, residing at Warren, in the county of Warren and State 5 of Pennsylvania, have invented new and useful Improvements in Oil Bailers, of which the following is a specification.

This invention relates to oil bailers and has for its principal object the construction 10 of a bailer valve which is seatless and therefore free from the defect of being held open by gravel or sand collecting on the seat as is the case with ordinary bailer valves.

Another object of the invention is the 15 construction of a bailer provided with a reciprocable gravity-operated piston valve, having lateral ports opening above the bottom of the bailer body, whereby said ports, and consequently the operation of said 20 valve, are unaffected by the sludge or such other sedimentary deposits as may collect in the bottom of the bailer body.

Another object of the invention is a bailer 25 having a detachable valve cage and a reciprocating valve, said valve having a flange adapted to abut against a shoulder on one end of said cage, said stem being provided with an arm engageable with a shoulder on the other side of the valve cage for the purpose 30 of limiting the movement of said valve in either direction.

The invention further consists in providing 35 an efficient construction and arrangement of parts and in the other matters hereinafter more fully described, reference being had to the accompanying drawings, in which:—

Figure 1 is a longitudinal view in cross 40 section of my improved bailer showing the valve in open position.

Figure 2 is an underneath plan view of the same.

Figure 3 is a longitudinal view partly in 45 cross section showing the valve in closed position.

Figure 4 is a cross sectional view taken along the line 4—4 of Figure 3.

Referring in detail to the several views 50 the numeral 1 represents the body of the bailer which is cylindrical in form and open to the atmosphere at the upper end 2. It is provided with the bail handle 3 riveted to the opposite sides of the cylindrical body at 4 by means of which the bailer is lowered into a well. Within the lower end of the bailer body is secured the ring 5 by means

of the rivet 6, said ring is provided at its lower end with a flange 7 forming an extending shoulder 8 against which the lower end of the body 1 abuts and is also provided 60 on that part of the exterior surface which is overlapped by the body with annular packing grooves 9.

The ring 5 is interiorly threaded at 10 for the reception of the valve cage 11. The 65 valve cage comprises a split cylindrical member having portions of several diameters, that part of the smaller diameter, 12 extending within the body 1 of the bailer and being provided with the lateral ports 70 13. The outer end of the valve cage 14, which is the largest diameter, abuts against the outer surface of the flanged portion 7 of the ring 5 while the portion 15 of intermediate diameter is threaded and engages 75 the threaded surface 10 of the ring 5. Between its ends the bore of the valve cage is restricted by the partition 16, said partition being provided with a circular aperture 17 therethrough surrounding the valve stem 18 80 and being cut away as at 27 forming radial arms 28 affording passages between said arms to permit the free entrance of liquid to the interior of the valve cage and bailer body.

To the upper end of the valve stem 18 is secured the piston valve 19 having the skirt portion 20 which is slidably fitted within the inner part 12 of the valve cage in a position to close or open the ports 13 in the act 90 of reciprocation. The piston valve 19 is provided with the extending flange 21 which abuts the inner end 22 of the valve cage limiting the downward movement of the piston valve and valve stem, and the latter is provided at its lower end with a crowfoot or spider 23 having radial arms 24 which abut against the outer end of the part 14 and limiting the upward movement of the piston valve and valve stem.

A strainer 25 is secured in any appropriate manner within the outer end of the valve cage and against the partition 16, said strainer being constructed with a circular aperture 26 which closely fits against the 100 valve stem 18.

In operation, the bailer is lowered to the bottom of the well. While suspended, gravity will cause the piston valve 19 to descend closing the ports 13. The valve stem 110 and crowfoot will then project in spaced relation from the outer end 14 of the valve

cage as shown in Figure 3. When the bailer reaches the bottom of the well, the crowfoot 23, coming in contact with said bottom, will cause the valve stem to move inwardly until 5 the arms 24 of said crowfoot abut against the outer end 14 of the valve cage. This will open the ports 13. Liquid from the well will then flow through the strainer and through the passages 27 into the valve cage 10 and then through the ports 13 upwardly into the bailer body which will be filled to as high a level as the liquid in the well will permit. Upon withdrawing the bailer from the well by means of the bail handle 3 the 15 piston valve will again close the ports 13 and the liquid within the bailer will be trapped, so that it may be raised to the top of the well. To empty the bailer it is merely necessary to set it upon the ground 20 upon the end of the crowfoot 23, whereupon the valve stem will be forced inwardly and the valve ports opened permitting the liquid to flow back from the bailer through the same channels by which it entered.

25 It will be obvious from the construction herein described that I have provided a seatless valve for the bailer and one in which it is impossible that sand or gravel should interpose itself between the fixed and moving ports of the valve, so as to permit the latter from closing. By the location of the ports 13 above the lowest part of the interior of the bailer body they will not be interfered with by the gradual accumulation 30 of sludge or other fine solid material which happens to pass through the strainer. By having the valve cage detachably engageable with the ring 5 it is possible to readily remove the valve and valve cage 35 from the bailer body should it be necessary at any time to have access to them for the purpose of making repairs.

Having described my invention what I claim as new and desire to secure by Letters Patent, is:—

45 1. A gravity-operated bailer comprising a hollow body, a valve cage detachably secured in the lower end of said hollow body, having a port communicating with space outside said body and a valve mounted in said valve cage for controlling said port and having an actuating stem projecting beyond the lower end of said body.

50 2. A gravity-operated bailer comprising a hollow body, a valve cage detachably secured in the lower end of said hollow body, having a port communicating with space outside said body and a valve mounted in said valve cage for controlling said port and having an actuating stem projecting beyond the lower end of said body, and a lateral arm on said stem, engageable with the lower end of said valve cage to limit the upward movement of said valve.

55 3. A gravity operated bailer comprising

a hollow body, a valve cage detachably secured in the lower end of said body, having a cylindrical portion thereof extending inwardly into said hollow body and spaced from the walls thereof, said inwardly extending portion being provided with a lateral port communicating with space outside said body, a reciprocatory valve controlling said port having an actuating stem projecting beyond the lower end of said body, and means on said valve and stem adapted respectively to engage the inner and outer ends of said valve cage to limit the reciprocatory movement of said valve in either direction.

60 4. A gravity operated bailer comprising a hollow body, a valve cage detachably secured in the lower end of said body, having a cylindrical portion thereof extending inwardly into said hollow body and spaced from the walls thereof, said inwardly extending portion being provided with a lateral port, a transverse partition in said valve cage having a central aperture, said port and aperture communicating with space outside said hollow body, a reciprocatory valve controlling said port having an actuating stem projecting through said aperture and beyond the lower end of said body and means on said valve and stem adapted respectively to engage the inner and outer ends of said valve cage to limit the reciprocatory movement of said valve in either direction.

65 5. A gravity operated bailer comprising a hollow body, a valve cage detachably secured in the lower end of said body, having a cylindrical portion thereof extending inwardly into said hollow body and spaced from the walls thereof, said inwardly extending portion being provided with lateral ports arranged at a higher level than the plane of the inner surface of the bottom of said hollow body, a transverse partition within said valve cage having a central aperture, said ports and said aperture communicating with space outside said hollow body, a reciprocatory valve having a cylindrical portion controlling said ports, and having an actuating stem projecting through said aperture and beyond the lower end of said body, and means on said valve and stem adapted respectively to engage the inner and outer ends of said valve cage to limit the reciprocatory movement of said valve in either direction.

70 6. A gravity-operated bailer comprising a hollow body, a valve cage detachably secured in the lower end of said body, having a cylindrical portion thereof extending inwardly into said hollow body and spaced from the walls thereof, said inwardly extending portion being provided with lateral ports arranged at a higher level than the plane of the inner surface of the bottom

- of said hollow body, a transverse partition within said valve cage having a central aperture, said ports and said aperture communicating with space outside said hollow body,
5 a strainer arranged outside of said partition and screening said aperture a reciprocatory valve having a cylindrical portion controlling said ports and provided with an actuating stem projecting through said aperture
10 and screen and beyond the lower end of said body and means on said valve and stem adapted respectively to engage the inner and outer ends of said valve cage to limit the reciprocatory movement of said valve in either direction.
